(57) **CLAIM**

The ornamental design for a camera device, as shown and described.

DESCRIPTION

FIG. 1 is a top, front, right side perspective view of a camera device, showing our new design;

FIG. 2 is a top, back, left side perspective view thereof;

FIG. 3 is a bottom, front, right side perspective view thereof;

FIG. 4 is a bottom, back, left side perspective view thereof;

FIG. 5 is front view thereof;

FIG. 6 is a right side view thereof;

FIG. 7 is a back side view thereof;

FIG. 8 is a left view thereof;

FIG. 9 is a top view thereof; and,

FIG. 10 is a bottom view thereof.

The broken lines in the drawings depict portions of the camera device that form no part of the claimed design.

1 Claim, 9 Drawing Sheets
